[57] **CLAIM**

The ornamental design for a combined closure dispenser and battery powered drink mixer for a container, as shown.

DESCRIPTION

FIG. 1 is a top rear perspective view of a combined closure dispenser and battery powered drink mixer for a container showing my new design;
FIG. 2 is a top plan view thereof;
FIG. 3 is a side elevational view thereof, a portion being omitted for convenience of illustration; and
FIG. 4 is a bottom plan view thereof.

The design has generally cylindrically exterior walls so that the hidden sides opposite those shown in FIGS. 1 and 3 are generally similar to that shown.
